SELF-RETAINING UTERINE CANNULA

Edward Kahn, Queens Village, N. Y.

Application October 11, 1948, Serial No. 53,880

9 Claims. (Cl. 128—348)

1

This invention relates to a self-retaining uterine cannula having improved tenaculum control, finger control, acorn stop, and shaft.

The cannula of the present invention is used primarily for insufflation of the Fallopian tubes with carbon dioxide gas, uterosalpingography with iodized oil for X-ray study of the uterus and appendages with tenaculum in a self-retaining manner or without tenaculum (cannula held in place by hand) for sounding of the cervico-uterine canal, and in the collection of smears under negative pressure by aspiration from the uterine canal in the detection of cancer.

The principal object of this invention is the provision of a self-retaining cannula with finger ring, which is suitable for use with a tenaculum (volsellum) forceps of any length, shape, or type especially tenacula of nine or ten inch length without increasing the length of the cannula over previous cannulae of its type.

A further object is to provide a cannula of the type described with which the tenaculum may be applied at any point on the circumference of the cervix without the necessity of removing the tenaculum control from the shaft of the cannula for re-application in a different radial position relative to it.

Another object of this invention is to provide a cannula whose tenaculum control and thumb ring are self-positioned with respect to the hands of the physician making use of the same.

Another object of the invention is for the first time to introduce a finger squeezing technique for setting the cannula with a tenaculum in a self-retaining position. In instruments of this general character heretofore known, the technique was haphazard and indefinite. A finger squeezing technique is safe because it can be controlled. A finger squeezing technique is less painful to the patient because there is less manipulation and jarring of tissue. A finger squeezing technique is faster to set the acorn in place or to release it decreasing the time of the test, as well as adding safety to the test.

Another object of this invention is to provide for the first time in instruments of this general character and introduce a definite technique for the introduction of the cannula past the cervix into the uterine canal with or without the use of a tenaculum. The technique consists of locking the tenaculum control at a point on its shaft which gives the physician the greatest sense of balance by thus changing the center of gravity of the instrument. With thumb through thumb ring and fore and middle fingers on the trigger

2

shaped finger grip, the beginner or more experienced physician is able to develop a deftness and sensitivity of touch to safely guide the tip of the cannula beyond the internal os into the uterine canal regardless of its angulation. Once in the uterine canal, by negative pressure on the cannula, cellular secretions may be aspirated for study in the early detection of cancer.

Still another object of this invention is the provision of a cannula of the character described whose tip is malleable but whose shaft is otherwise rigid.

Other objects will become apparent from a reading of the specifications and an examination of the drawings. The drawings disclose preferred embodiments of this invention, setting them forth in the following figures:

Fig. 1 is a sectional view showing the cervicouterine canal and vagina and the speculum, tenaculum and cannula in operative position therein.

Fig. 2 is a side view of the cannula herein claimed.

Fig. 3 is a top view thereof.

Fig. 4 is a sectional view through the tip thereof as well as through the sealing and limiting members mounted thereon.

Fig. 5 is a fragmentary side view showing how the tenaculum is engaged by the tenaculum control member which is adjustably mounted on the cannula.

Fig. 6 is a top view of the tenaculum showing it in engagement with the tenaculum control member of the cannula.

Fig. 7 is a view of the prongs or teeth of the tenaculum.

Fig. 8 is a sectional view on the line 8—8 of Fig. 2, through the limiting member which is also adjustably mounted on the cannula proper.

Fig. 9 is an enlarged fragmentary view of a cannula on which a ratchet is provided for adjustably positioning the tenaculum control member thereon; and

Fig. 10 is a plan view of a finger ring which may be substituted for the set screw on the limiting member in Fig. 1.

Referring now to the first eight figures of the drawing, it will be seen that a cannula 10 is used in conjunction with two other instruments, to wit, a speculum 11 and a tenaculum 12, with respect to a passage 13 of the human body 14. For purposes of illustration, the passage shown is the cervico-uterine canal 23 in which the cervix 36 is disposed.

A conventional tenaculum may be used with

cannula 10, but more satisfactory results will flow from the employment of tenaculum 12 whose jaws or prongs 15 are shown in Fig. 7 to be specially shaped. More specifically, they are shown to be offset from the shafts 16 and 17, respectively, of the instrument. The shanks of the tenaculum are also shown to be bent and offset at 18 which is a point intermediate the fulcrum 19 and rings 20. By reason of such construction, the jaws are enabled to grasp the cervix at any point of its periphery in such manner as to provide stronger grip-less trauma, more maneuverability, greater visibility. Furthermore, additional room and visibility are placed at the service of the physician.

It will also be apparent from said Fig. 5, as well as from Figs. 1 and 6, that a crossbar ratchet 21 is provided adjacent rings 20 of the tenaculum, and it will be understood that this is the means by which interengagement between the cannula and the tenaculum is generally provided. Interengagement may also be obtained on the front or back of the rings 20.

The cannula 10 herein claimed includes a stainless steel tubular shaft 38 from which, at 31, the brass cannula extends to the very tip of nozzle 32. The tip is bent as shown in Figs. 2 and 4 to conform to the curvature and direction of the cervical canal by annealing the last three-quarters of an inch to render it suitable for further bending, as and when desired. The tip 32 is provided with fenestrations 34 at its end and on each side opposite each other. Slidably mounted on the cannula shaft which is identified in the drawing by means of the reference character 33, is a plug or rubber acorn 35 which is used for sealing the opening to the cervical canal after the tip has been introduced therein. An acorn stop 37 is also slidably mounted on said reduced portion of the shaft, behind the sealing member 35. A set screw 38 is provided in said stop for engagement with said shaft to fixedly position the stop on the shaft. When the collar 37 is so positioned on the shaft, it serves as a stop or limiting member for the plug or sealing member 35, preventing it from moving backwardly along said shaft beyond a predetermined or selected point. It has a boss 39 to allow longer thread for set screw 38.

At the opposite end of the cannula shaft is the inlet opening through which the cannula may be connected by a Luer connection to a source of supply of the liquid or gas which it is desired to introduce into the cervical canal. A valve 40 is connected to the cannula shaft adjacent its said inlet opening. This valve is used to control the flow of liquid or gas through said shaft.

Slidably mounted on the proximal outer stainless steel shaft, forward of valve 40, are two control members: the tenaculum control member 45 and the thumb ring limiting or stop member 46 for said tenaculum control member, said limiting or stop member being disposed between the valve and said tenaculum control member. These two members are mounted on the cannula shaft not only for longitudinally slidable movement thereon, but also for pivotal movement thereon, radially thereof. They are movable relatively to the shaft and to each other. Each by design has a plumb bob action which tends to direct the wing of the tenaculum control upwardly and the thumb ring of the stop member 46 downwardly, irrespective of the relative position of the cannula shaft, a set or thumb screw on each being provided for fixedly positioning it on said cannula shaft, as and where desired.

More specifically, the tenaculum control member is provided with a body portion 50 which is hollow or tubular to accommodate the cannula shaft. A relatively heavy long thumb screw 51 is connected to said body portion for engagement with the cannula shaft. Boss 49 is provided on the body portion to afford a longer threaded bearing for the screw 51. This thumb screw performs three functions: it serves as a weight which tends to hold the tenaculum control member in a vertical position, as shown in Figs. 1 and 2; it serves as a clamping means by which the tenaculum control member may be fixedly positioned at any point of long axis or circumference of said cannula shaft; by its length and breadth and its longitudinal serrations it can be released almost instantaneously for the emergency escape of gas or liquid.

Extending upwardly from the body of said tenaculum control member is a notched wing 52 adapted to engage the crossbar or a ring of the tenaculum as shown especially in Figs. 1 and 6, at 52, 52a and 52b. Each of its notches 54 is adapted to accommodate said tenaculum crossbar or ring and a plurality of such notches is provided for varying the spacing between the cannula and the tenaculum or the angle of the tenaculum on the cervix.

Extending downwardly from the body of the tenaculum control member, to accommodate the fore and middle fingers, is a finger grip shaped like a trigger 53, spaced forwardly of the thumb screw 51, and lying in a common plane therewith. It is by means of this finger grip that the physician, with thumb through thumb ring, is enabled to (1) balance the cannula for introduction into the uterus, and (2) use the tenaculum as an anchor as he forces the previously set acorn into the opening of the cervix and retain it in position, occluding the external os of cervix to prevent backflow of gas or liquid.

The thumb or stop member 46 also serves to shorten the gap on the shaft between itself and the tenaculum control body—a safety feature to prevent a harpooning perforation of the uterus if the acorn stop slipped while occluding the cervix—driving the tip deeper into the uterus than intended by the operator. This limiting member also includes a hollow or tubular body 55 having a set screw 56 connected thereto for engagement with the cannula shaft. Depending from said body portion is a relatively comfortably rounded heavy ring 57. This ring also performs two functions: it serves as a finger ring for the physician's thumb in substantially the same manner as member 53 serves as a fingerpiece for the physician's forefinger and middle finger, and it also serves as a weight which tends to hold said limiting member 55 in the vertical position which it is shown to occupy in Figs. 1 and 2. This limiting member 55 may be fixedly positioned on the cannula shaft at any predetermined or selected place thereon to limit the movement of the tenaculum control member, backwards on the shaft. As indicated above, this is an added safety feature. The position of said limiting member on said cannula shaft will normally be determined by the extent to which penetration is desired and by the relative lengths of the tenaculum and the cannula shaft.

To afford a relatively long threaded bearing for the set screw 56, the body 55 is provided with a hub or boss 58 which is threaded to receive the set screw 56 or as an alternative, the ring 56a (Fig. 10), where it is desired to use two rings for the index and middle finger to react against the

pressure of the thumb on the plunger of a syringe which may be attached to the valve 40.

It will be noted that the thumb screw 51 is a relatively long, knurled member which is positioned intermediate finger-pieces 53 and 57. It is thus in a happily convenient location when it is desired to quickly release it. This feature is extremely important since very frequently it becomes necessary to provide for immediate release of the gas or liquid in the uterus and appendages. When this thumb screw 51 is loosened, the cannula is free to move outwardly with respect to the cervical canal, thereby removing the plug or sealing member 35 from its opening.

The foregoing is descriptive of a preferred form of this invention and other forms may be provided within the broad scope of the invention. Illustrative of the modifications which may be incorporated into the present device is the ratchet construction shown in Fig. 9. It will there be noted that a cannula shaft 60, in all other respects similar to the cannula shaft above described, is provided with a plurality of ratchet teeth 61. A tenaculum control member 62 is slidably mounted on said cannula shaft and it is provided with a pawl 63 urged by spring 64 into engagement with said ratchet teeth 61. The tenaculum control member is accordingly free to move backwardly, as shown in Fig. 9, or stated differently, the cannula shaft is free to move forwardly through said tenaculum control member for insertion into the body. When it is desired to release the cannula shaft for backward movement through said tenaculum control member, the pawl is pulled out of engagement with the ratchet teeth. It will be observed that this pawl and ratchet construction is designed to take the place of thumb screw 51 above referred to. Also as shown in Fig. 9 the tenaculum control member 62 and the ring member 65 may be so mounted on the cannula shaft as to prevent them from pivoting thereon. Indeed the ring member is shown to be fixedly mounted on said cannula shaft and thereby prevented from engaging in any kind of movement relative thereto.

If desired, thumb ring set screw 56 may be replaced with a threaded shank ring 56a, so that ring or rings may be used in the former manner to support forefinger and middle finger while the thumb pushes an attached syringe piston.

Other modifications and variations will be apparent to those skilled in the art. By way of illustration, the finger-piece on tenaculum control member 45 may be made sufficiently heavy to enable it to serve as the weight by which said control member is maintained in a vertical plane, thereby rendering it unnecessary to provide a heavy thumb screw for the same purpose. The materials of which the instruments herein above described may be made will be determined by the use to which the materials will be put in these said instruments. For example, the tubular shaft of the cannula should preferably be made of a relatively rigid material such as stainless steel. Its inner shaft portion or cannula proper should be made of a relatively malleable material such as brass or a suitable alloy of metals similarly malleable. The plug or sealing member 35 should be made of rubber, and brass will suffice for the other parts of the cannula, and surgical steel for the tenaculum.

Having thus described my invention, what I

claim as new and desire to secure by Letters Patent, is:

1. A cannula of the character described comprising a tubular shaft having an inlet opening and a valve at one end, and a tip at the opposite end, a sealing acorn slidably mounted on said cannula shaft adjacent said tip, an acorn stop adjustably mounted on said shaft, a tenaculum control member adjustably mounted on said shaft adjacent said valve and inlet opening and a thumb ring limiting member for said control member also adjustably mounted on said shaft, intermediate said control member and said valve and inlet opening.

2. A cannula of the character described comprising a tubular shaft having an inlet opening and a valve at one end and a tip at the opposite end, a sealing acorn slidably mounted on said cannula shaft adjacent said tip, a tenaculum control member adjustably mounted on said shaft adjacent said valve and inlet opening and a thumb ring limiting member for said control member also adjustably mounted on said shaft, intermediate said control member and said valve and inlet opening, said control and limiting members being mounted on said cannula shaft for slideable movement relative thereto and relative to each other and for pivotal movement about said shaft, set screws being provided to fixedly position said control and thumb ring limiting members on said shaft.

3. A cannula of the character described comprising a tubular shaft having an inlet opening and a valve at one end and a tip at the opposite end, a sealing member slidably mounted on said cannula shaft adjacent said tip, a tenaculum control member adjustably mounted on said shaft adjacent said valve and inlet opening and a limiting member for said control member also adjustably mounted on said shaft, intermediate said control member and said valve and inlet opening, said control and limiting members being mounted on said cannula shaft for slideable movement relative thereto and relative to each other and for pivotal movement about said shaft, set screws being provided to fixedly position said control and limiting members on said shaft, said limiting member being provided with a thumb ring and said control member being provided with a cooperating trigger-like finger grip, whereby relative movement between the cannula shaft and the tenaculum control member may be provided when the set screw of said control member is in released position and the set screw of the limiting member is in clamping position.

4. A cannula in accordance with claim 3 wherein the set screw of the control member and the ring of the limiting member are weighted to hold said members in a common vertical plane, 60 when the set screws of both members are in released position, irrespective of the relative position of the cannula shaft.

5. A cannula in accordance with claim 3 wherein an acorn stop is slidably mounted on said cannula shaft behind said sealing member, said stop serving as a limiting member for said sealing member and being provided with a set screw for fixedly positioning it on said cannula shaft.

6. A cannula of the character described comprising a tubular shaft having an inlet opening at one end and a tip at the opposite end, a sealing member slidably mounted on said shaft adjacent said tip, a tenaculum control member and a thumb ring member adjustably mounted on

said shaft adjacent said inlet opening, said control and thumb ring members being weighted to maintain them in a common vertical plane irrespective of the relative position of said cannula shaft, set screw means being provided to adjustably fixedly position said control and thumb ring members on said cannula shaft when desired.

7. A cannula in accordance with claim 6 in which the posterior portion of the cannula shaft is made of relatively rigid material, and the anterior and tip portion are made of relatively malleable material, whereby said tip may be bent in accordance with individual requirements.

8. Surgical instrument means of the character described comprising a cannula and a tenaculum cooperating therewith, said cannula comprising a tubular shaft having an inlet opening at one end and a fenestrated tip at the opposite end, a sealing member slidably mounted on said shaft adjacent said tip, a tenaculum control member and a thumb ring member adjustably mounted on said shaft adjacent said inlet opening, said control and thumb ring members being mounted on said shaft for slidable movement thereon and for pivotal movement thereabout and being weighted to maintain them in a common vertical plane irrespective of the relative position of the shaft, clamping means being provided to adjustably fixedly position said members on said shaft, said tenaculum control member having a notched wing extending upwardly therefrom and said tenaculum having a cross-bar and finger rings which are selectively engageable with the notches in said notched wing, said tenaculum being also provided with a pair of pivotally connected shanks having said cross bar and the pair of finger rings at one end and

pointed teeth at the opposite end, said shanks being bent and offset intermediate said pivotal connection and said cross bar, and said pointed teeth being bent and offset from their respective shanks.

9. A cannula of the character described comprising a tubular shaft having an inlet opening at one end and a tip at the opposite end, a sealing member slidably mounted on said shaft adjacent said tip, a stop member for said sealing member adjustably mounted on said shaft and a tenaculum control member and a thumb ring member mounted on said shaft adjacent said inlet opening, said thumb ring member being fixedly mounted on said shaft and said tenaculum control member being slidably mounted on said shaft, a pawl and ratchet means being provided whereby relative movement between the shaft and the tenaculum control member may be had in one direction but not in the opposite direction unless the pawl is in released position.
